UNITED STATES PATENT OFFICE.

EDWARD E. DAILEY, OF NEEDHAM HEIGHTS, MASSACHUSETTS.

BOX-COVERING MACHINE.

1,100,228.

Specification of Letters Patent. Patented June 16, 1914.

Application filed May 6, 1912. Serial No. 695,368.

To all whom it may concern:

Be it known that I, EDWARD E. DAILEY, a citizen of the United States, and a resident of Needham Heights, in the county of 5 Norfolk and Commonwealth of Massachusetts, have invented an Improvement in Box-Covering Machines, of which the following description, in connection with the accompanying drawings, is a specification, 10 like characters on the drawings representing like parts.

My invention relates to machines for handling sheet material, being more particularly concerned with machines for applying 15 an adhesive material to a strip of paper or cloth, and winding the strip about the sides of boxes or other articles.

My invention will be best understood by reference to the following description, when 20 taken in connection with the accompanying illustration of one specific embodiment thereof, while its scope will be more particularly pointed out in the appended claims.

In the drawings:—Figure 1 is a side elevation of a box covering machine embodying my invention. Fig. 2 is a detail sectional view partly in elevation on lines 2—2 of Fig. 1. Fig. 3 is a detail section at an enlarged scale on line 3—3 of Fig. 1. Fig. 30 4 is a plan of the glue pan and adjacent devices. Fig. 5 is a detail section on line 5—5 of Fig. 1.

Referring to the drawings and to the embodiment of my invention which I have 35 there shown for illustrative purposes, I have there shown a box covering machine having a suitable frame 5 for supporting the operative parts of the machine, and on this frame is mounted a suitable device for applying the glue or other adhesive material 40 to the paper, cloth, or other sheet material, this device herein comprising a roll 6, receiving its supply of glue from a suitable reservoir 7, the roll for this purpose being 45 partly submerged in the glue. A strip, or strips, 8 of sheet material may be fed from any suitable source of supply, such for example as a roll, or rolls, 9 across and in driving contact with the periphery of the glue 50 roll 6 by any suitable means, such for example as a rotating form 10, the latter being herein suitably constructed to receive the sides of the box blank, and being mounted to rotate on a suitable head 11. This 55 head may be adjustably mounted in any suitable manner, but since the head *per se*

forms no part of my present invention, it will be unnecessary to further describe the same herein.

The rotating form 10 may be rotated by 60 any suitable means, herein being driven by a pair of beveled gears 12 and 13, the former being secured to the shaft 14 of the form, and the latter being secured to a shaft 15. The shaft 15 is driven by suitable means, 65 such for example as a worm gear 16 meshing with a worm 17 secured to a driving shaft 18. This shaft carries a constantly rotating loose pulley 19, which may be driven from any suitable source of power 70 not shown, and constitutes one member of a clutch. The other clutch member 20 is splined on the driving shaft 18, and is normally held out of driving engagement with the member 19 by a suitable spring 22 75 interposed between the said members. Mounted in suitable guides 23 and 24, is a clutch-shifting rod 25, under the control of the operator through a treadle 26, treadle-rod 27 and bell-crank lever 28, having an arm 29 80 bearing against one end of the clutch shifting rod 25. The clutch-shifting rod is provided with suitable means for controlling the shiftable clutch member 20, herein consisting of a member 30 secured to said rod 85 and engaging said clutch member in such a manner as to force the latter against the tension of the spring 22 into driving engagement with the clutch member 19. Suitable means are provided for stopping the 90 feeding motion of the feeding means by stopping the rotation of the driving shaft 18 when the clutch is disengaged, said means herein comprising a friction disk 31, secured to and driven by said shaft, and a non-rotat- 95 ing friction disk 32 carried by the clutch-shifting rod 25. A suitable spring 33 is arranged to urge the friction disk 32 into engagement with the friction disk 31 simultaneously with the disengagement of the 100 clutch members.

Interposed between the glue roll 6 and the rotating form 10 are suitable instrumentalities for severing the strip of paper, herein comprising a fixed knife 34 and a co-operating movable knife 35, actuated by suitable means, such for example as an arm or arms 36 secured to a rock-shaft 37. Secured to this rock shaft is a gear 38, meshing with a gear 39, secured to a 110 rock shaft 40 journaled in suitable bearings in a bracket 41 forming part of

the frame of the machine. Secured to the rock shaft 40 is an arm 42, to which is connected the upper end of a rod 43, the lower end of said rod being pivotally connected to a cam lever 44 secured to a rock-shaft 45. The cam lever 44 coöperates with a suitable cam 46, and for that purpose is herein provided with a protuberance 47, engaging the periphery of the cam, the latter being provided with a depression 48 of suitable depth and extent to allow the cam lever to drop at the proper time in the operation of the machine and actuate the movable knife 35 to coöperate with the stationary knife 34 to sever the strip of paper or other material. Secured to the rock-shaft 45 is an arm 49, to which is secured one end of a suitable spring 50, the other end being secured to a suitable fixed point, as for example a pin 51 on the frame of the machine, this spring assisting in the downward movement of the knife 35 and its connected parts. The cam 46 is secured to a shaft 52 driven by a worm gear 53, also secured thereto and meshing with the worm 17. It will thus be seen that the knives are caused to operate to sever the paper at a pre-determined time in the operation of the machine.

Located beneath and preferably contacting with the arm 49 is an arm 54 secured to a rock-shaft 55, mounted in suitable bearings 56 and 57 on the frame of the machine. Secured to this rock-shaft is an arm 58 connected by suitable means, herein links 59 and 60 to a brake-shoe 61, engaging a brake-drum 62 secured to the shaft of the glue roll 6. The brake-shoe may, if desired, be provided with a suitable lining 63 of leather or other suitable material. The brake-shoe 61 may be constructed in any suitable manner, so as to normally remain out of engagement with the brake-drum 62, and for that purpose is herein made of resilient material, so that it is normally lifted from the brake-drum. It will now be apparent that when the strip of material is being fed by the rotation of the form 10, the strip will be fed across and in driving contact with the glue roll 6, so as to rotate the latter, and therefore apply the glue or other adhesive matter to the strip of paper. But when the rotation of the form ceases, and the strip of material is severed by the knives, the rotation of the glue roll will be instantly and automatically stopped by the action of the brake, so as to prevent over-travel due to the inertia of the drum. This device therefore overcomes one very serious fault in machines of this class heretofore, namely, the over-travel of the glue roll, which results in the paper or other material continuing to feed forward under the influence of the roll and form a slack between the roll and the knives. This is very undesirable for the reason that it spoils the tension on the material, as well

as wasting the glue or other adhesive material, and often causes the strip to disengage from the roll and thus cause portions of the strip to remain uncoated.

There may be provided any usual or desired means for guiding the strip or strips of material, and "stripping" or scraping off the excess adhesive material therefrom. For this purpose, I have shown a usual guide 64, adapted to guide the strip or strips 8 of material from the supply roll or rolls 9 to the glue roll 6, a usual guide and stripper 65 adapted to guide the strips and remove the excess glue so that the latter will return to the reservoir 7, an auxiliary stripper 66, with a receiver 67 for the drippings, and a guide 68. These parts are all of the usual construction, and act in the usual and well-known manner to cause the coated strips to be delivered to the winding form "tempered", or partially dried, so as to properly adhere to the box blank.

While I have herein shown and described one form of my invention for illustrative purposes, and have disclosed and discussed in detail the construction and arrangement incidental to one specific application thereof, it is to be understood that the invention is limited neither to the specific embodiment herein shown nor to the mere details or relative arrangement of parts, but that extensive deviations from the illustrated form or embodiment of the invention may be made, without departing from the principles thereof.

Having thus described one embodiment of my invention, what I claim and desire by Letters Patent to secure is:

1. A machine for handling sheet material having in combination, means to support a supply of sheet material, means for coating the sheet material, means for feeding the material from the source of supply past the coating means, said coating means being interposed between said feeding means and said supporting means, means to stop the motion of said feeding means, and means to hold the material against longitudinal movement when the motion of the feeding means ceases.

2. A machine for handling sheet material having, in combination, a roll for applying liquid to the sheet material, means for feeding the sheet material from a source of supply across and in contact with said roll to drive the latter, means permitting cessation of the operation of said feeding means, and means for automatically stopping the rotative movement of the roll and holding the same against movement in the direction of the feeding movement when the feeding movement of the material under the influence of the feeding means ceases.

3. A machine for handling sheet material having, in combination, a roll for applying

- liquid to the sheet material, means for feeding the sheet material from a source of supply across and in driving contact with the periphery of the roll, means severing the sheet material, and means to hold the material against longitudinal movement when the material has been so severed. 5
4. A machine for handling sheet material having, in combination, a roll for applying liquid to the sheet material, means for feeding the sheet material from a source of supply in driving contact with the periphery of said roll, means to stop the feeding motion of said feeding means, and mechanism including a brake for automatically stopping the rotation of said roll in the direction of the feeding movement when the operation of the feeding means ceases. 10
5. A machine for handling sheet material having, in combination, a roll for applying liquid to the sheet material, means for imparting a longitudinal feeding movement to the sheet material to draw the latter across the periphery of the roll in driving contact therewith, means located between the roll and feeding means for severing the material, and means for automatically stopping the rotation of the roll simultaneously with the severing of the material. 15
6. A machine for handling sheet material having, in combination, a roll for applying liquid to the material, means including a rotating body for feeding the sheet material across the periphery of the roll in driving contact therewith, means to stop the rotation of said body, and means for stopping the rotation of said roll in the direction of the feeding movement when the rotation of the rotating body ceases. 20
7. A machine for handling sheet material having, in combination, a roll for applying liquid to the sheet material, means including a power-driven body for feeding the sheet material from a source of supply in driving contact with the periphery of the roll, means to stop said body, and means for automatically stopping the rotation of the roll in the direction of the feeding movement when the rotation of said body ceases. 25
8. A machine for handling sheet material having, in combination, the roll 6 for coating the sheet material, the winding form 10, the brake 61, and mechanism connecting the form and roll for applying the brake to stop the roll. 30
9. A machine for handling sheet material having, in combination, the roll 6 for coating the sheet material, the winding form 10, the brake 61, the cam 46, connections between said cam and form, and means actuated by the cam for applying the brake to stop the roll. 35
10. A machine for handling sheet material having, in combination, means to support a supply of the sheet material, means for coating the sheet material with liquid, means for feeding the material from the source of supply past the coating means, means permitting cessation of the operation of said feeding means, and means to make said coating means effective to bring the material to a state of rest when the operation of the feeding means ceases. 40
11. A machine for handling sheet material having, in combination, a roll for applying liquid to the sheet material, means for feeding the sheet material from a source of supply across and in contact with said roll to drive the latter, means permitting cessation of the operation of said feeding means, and means automatically to bring said roll to a state of rest when the feeding movement of the material under the influence of the feeding means ceases. 45
12. A machine for handling sheet material having, in combination, a roll for applying liquid to the sheet material, means for feeding the sheet material from a source of supply across and in driving contact with the periphery of the roll, means for severing the sheet material, and means for bringing the material to a state of rest when it has been so severed. 50

In testimony whereof, I have signed my name to this specification, in the presence of two subscribing witnesses.

EDWARD E. DAILEY.
